UNITED STATES PATENT OFFICE.

JAMES B. EVANS, SR., OF FORT WORTH, TEXAS.

RAIL-JOINT.

1,093,555.

Specification of Letters Patent. Patented Apr. 14, 1914.

Application filed July 18, 1913. Serial No. 779,826.

To all whom it may concern:

Be it known that I, JAMES B. EVANS, Sr., a citizen of the United States, residing at Fort Worth, in the county of Tarrant and State 5 of Texas, have invented new and useful Improvements in Rail-Joints, of which the following is a specification.

The present invention relates to improvements in rail joints, the object being to so 10 construct and arrange the meeting ends of two railway rails as to provide interlocking members which, when assembled, will effectively sustain the said rails at their meeting ends against lateral movement or vertical 15 depression; to effectively retain the heads of the rails in proper alignment so that the clicking of the wheels of the rolling stock passing over the joints, and the chipping of the rail ends, incident thereto are effectively 20 obviated, and finally wherein the employment of fish plates or like devices for connecting the rail ends is also dispensed with.

With the above objects in view, and others which will appear as the nature of the invention 25 is more fully understood, the improvement consists in the construction, combination and arrangement of parts set forth in the following specification and falling within the scope of the appended claims.

20 In the drawings there has been illustrated a simple and satisfactory reduction of my improvement to practice, and in which drawings:

Figure 1 is a side view of two rails constructed and connected in accordance with the present invention, Fig. 2 is a central longitudinal sectional view through the same, Fig. 3 is a transverse sectional view on the line 3—3 of Fig. 1, Fig. 4 is a similar sectional view on the line 4—4 of Fig. 1, Fig. 5 is an elevation looking toward the opposite side of the joint to that disclosed in Fig 1, Fig. 6 is a perspective view of one of the rail ends, and Fig. 7 is a similar view of the 45 second or co-acting rail end.

The rails are indicated by the letters R and R'. The body portions of the rails are of the ordinary construction, but the opposite sides of each of the rails are provided 50 with enlarged webs 1 and 2 respectively, the inner face of each of the webs being arranged centrally of the webs proper, and the said webs proper terminate in right angular shoulders 3 and 4 respectively which 55 are disposed a suitable distance beyond the ends of the head and the base flanges of the

rails, and the said heads and base flanges extend a suitable distance beyond the ends of the web enlargements. The enlargements 1 and 2 have their outer faces at both their upper and lower longitudinal edges formed with outwardly extending flanges 5 and 6, so as to provide the upper and lower edges of said extensions with flat bearing faces 7 and 8 respectively, the said faces projecting beyond the ends of the heads and base flanges a distance equaling the distance of the shoulders 3 from the said heads and base flanges, and the bearing face of the rail R' is adapted to be received between the head and the base 60 flange of the rail R and the end of its web extension is adapted to abut with the shoulder 3. When in such position, it will be noted that the bearing faces 7 and 8 of the rail R engage between and contact with the 65 underface of the head and the upper face of the base flange of the rail R' and the end of its web enlargement contacts with the shoulder 4 of the web proper of the rail R'. The enlarged web extensions are provided with 70 registering openings 9, for the reception of the ordinary securing bolts 10 and retaining nuts 11 therefor. By reference to Figs. 1 and 6 of the drawings it will be noted that both the head and base flanges of the rail 75 ends upon which the shoulders 3 are formed, have enlarged or reinforcing portions 12 which terminate even with the said angular shoulders and which provide additional 80 abutments for the ends of the co-acting web 85 extensions and end flanges.

From the above description, taken in connection with the accompanying drawings, the simplicity of the device, as well as the advantages thereof will, it is thought, be 90 perfectly apparent to those skilled in the art to which such inventions appertain without further detailed description.

Having thus described the invention, what I claim as new is:

1. In a rail joint, two rails, each of said rails having a web enlargement upon one of its faces and which is offset from the web proper to provide the end of the web proper with a shoulder, the head and the base flange 100 of each of the rails terminating a distance beyond the shoulders of the webs and a distance from the ends of the web extensions, the outer face of each of the enlarged web extensions having reinforcing flanges to provide both the upper and lower faces of the 105 extensions with flat bearing faces, the said 110

bearing faces of one of the rails adapted to be received between the head and base flanges of the second rail having the end of its web extension contact with the shoulder 5 of the second rail and the head and base flanges of both the rails abut, and means for connecting the web extensions.

2. In a rail joint, two rails, each of said rails having a web enlargement upon one of its faces and which is offset from the web proper to provide the end of the web proper with a shoulder, the head and base flange of each of the rails having enlargements which are arranged parallel with the shoulder to 10 provide continuations of the said shoulders, the head and the base flange of each of the rails terminating a distance beyond the shoulders of the webs and a distance from

the ends of the web extensions, the outer face of each of the enlarged web extensions having reinforcing flanges to provide both the upper and lower faces of the extensions with flat bearing faces, the said faces of one of the rails adapted to be received between the head and base flange of the second rail 20 and to have the end of its web extension contact with the shoulder of the second rail when the heads and base flanges of both the rails abut, and means for connecting the web extensions.

In testimony whereof I affix my signature in presence of two witnesses.

JAMES B. EVANS, SR.
